UNITED STATES PATENT OFFICE.

TRACY D. HOBBS, OF KALKASKA, MICHIGAN.

DESIGN FOR A LACE OR RIBBON HOLDER.

SPECIFICATION forming part of Design No. 31,523, dated September 19, 1899.

Application filed April 20, 1899. Serial No. 713,800. Term of patent 14 years.

To all whom it may concern:

Be it known that I, TRACY D. HOBBS, a citizen of the United States, residing at Kalkaska, in the county of Kalkaska, State of Michigan, have invented and produced a new and original Design for Lace or Ribbon Holders, of which the following is a specification, reference being had to the accompanying drawings, forming part thereof.

Figure 1 is a front elevation of my new design for lace or ribbon holders. Fig. 2 is a vertical central section of the same.

As shown in the drawings, the leading or material feature of my design consists of a series of rows of holders divided throughout their length at intervals by depressions, upon which ribbon, lace, or kindred goods may be wound. These holders extend from one side of the frame to the other, the ends being sup-

ported in the side pieces of the frame of the holder, while said side pieces are connected at the top and at the bottom by cross-pieces, as shown. The upper ends of the side pieces terminate in a scroll. (Best seen in Fig. 2.) The whole case is mounted upon legs, between which extends grillwork, as shown. The outer case or frame of the holder is surmounted by an ornamented head-piece, as seen in Fig. 1.

Having described my invention, what I claim as new, and desire to secure by Letters Patent, is—

The design for a lace or ribbon holder, as herein shown and described.

TRACY D. HOBBS.
